UNITED STATES PATENT OFFICE.

WILLIAM EDWARD BOEHCK, OF JERSEY CITY, AND HENRY SHELDEN GERMOND, JR., OF BAYONNE, NEW JERSEY, ASSIGNORS TO NEW YORK REVOLVING PORTABLE ELEVATOR COMPANY, OF JERSEY CITY, NEW JERSEY, A CORPORATION OF NEW JERSEY.

SECTION-LOCKING MECHANISM FOR PORTABLE ELEVATORS.

1,197,597.

Specification of Letters Patent. Patented Sept. 12, 1916.

Application filed April 19, 1913. Serial No. 762,302.

To all whom it may concern:

Be it known that we, WILLIAM EDWARD BOEHCK, a subject of the Emperor of Germany, residing at Jersey City, in the county 5 of Hudson and State of New Jersey, and HENRY SHELDEN GERMOND, Jr., residing at Bayonne, in the county of Hudson and State of New Jersey, a citizen of the United States of America, have invented certain 10 new and useful Improvements in Section-Locking Mechanism for Portable Elevators, of which the following is a specification, reference being had to the accompanying drawings.

15 This invention relates to improvements in portable elevators or tiering machines and particularly to improvements in portable elevators which are sectional in construction; and an object of this invention is to 20 provide simple and efficient manually-operated means for raising and lowering the upper hinged section of a sectional portable elevator and for locking this section in place in normal or operative position.

25 Another object of this invention is the provision in a portable elevator having electrically-operated windlass mechanism, of automatic means for giving to the switch-operating cable sufficient slack to permit the 30 upper section to be lowered without putting the cable under undue tension.

A third object of this invention is the provision in a portable elevator having electrically-operated windlass mechanism, of 35 means for automatically throwing the electric motor out of operation and setting the brakes at the upper and lower limits of travel of the load-carrying platform and releasing the brakes while the motor is 40 running.

In the drawings illustrating the principle of this invention and the best mode now known to us of applying that principle, Figure 1 is an interior side elevation partly in 45 section of so much of a portable elevator as is necessary to illustrate this invention the section being taken on the line A—A of Fig. 2; Fig. 2 is a fragmentary front elevation of the upper portion of the elevator, the view being taken in the direction of the arrow B in Fig. 1; Fig. 3 is a section on the 50 line C—C of Fig. 2; Fig. 4 is a fragmentary rear elevation, partly in section, of the base

portion of the elevator, the load-carrying movable platform being omitted; Fig. 5 is a 55 section on the line D—D of Fig. 4, the platform being shown in position; and Fig. 6 is an elevation, partly in section, of the brake mechanism.

The base *a* is mounted upon a truck (not 60 shown) and from this base *a* rise the side standards *b* within which is guided the platform *c*. This platform is raised and lowered by means of windlass mechanism *d* which in the particular case illustrated in 65 the drawings is driven by an electric motor *e*. The platform-hoisting cable *f* passes over the sheave *g* of the block *h*, one end of the hoisting cable *f* being attached to the platform *c* and its other end being wound 70 upon the windlass-drum *i*. At the upper end of each of the standards *b* there is fastened a plate *j* to which is hingedly secured at *k* the upper frame section *m* comprising side standards *b'* connected by transverse 75 frame members *b''* and braces *b**. Pivotally mounted in the top part of the section *m* is a U-shaped section-locking frame *n* consisting of a pair of arms *o* connected by the yoke *p*. When the locking frame *n* is 80 in its normal or locking position, the yoke *p* lies under the plates *j* (Fig. 3) of the main frame and is held securely in this position by means of a gravity-controlled catch *q*. When it is desired to lower the 85 upper section *m*, the locking frame *n* is thrown outwardly as is indicated by the dotted lines in Fig. 1; and the workman by pulling upon the locking frame *n* tilts the upper section *m*. After the latter has 90 reached that point where its center of gravity lies outside of the pivotal points *k*, the workman uses the locking frame *n* as a means for supporting the hinged upper section *m* in order that the descent of the same 95 may be controlled and made gradual. The arrangement of parts so far described may be used whether the windlass mechanism is manually operated or power-operated.

In case the windlass mechanism is electrically driven, provision is made for throwing the electric motor *e* and the brake mechanism controlling the windlass-drum shaft out of operation at the upper and lower limits of travel of the platform *c*. In 105 the top of the upper hinged section and at

one side thereof, there is journaled a rock-shaft r to one end of which is fastened a rocker-arm s having at its free lower end a roller t and to the other end of which is fastened a rocker-arm u which carries a sheave v . Near the base of the elevator there is mounted a pulley w ; and over the pulleys v, w passes an endless cable x upon which is fastened a pair of stops x', x'' one of which is near the upper limit of travel of the platform and the other of which is at the lower limit of travel thereof. Journaled near the bottom and at one side of the main frame is a brake-and-switch controlling shaft y upon which is mounted fast an operating arm y' the outer end of which is fastened to the controlling cable x . The platform c carries an arm 2 formed with an eye $2'$ through which passes freely the endless controlling cable x . At each limit of its travel, the arm 2 of the platform c strikes one of these stops x', x'' , moves the cable x and throws the operating arm y' , whereby the motor-current is interrupted and the brake mechanism (Fig. 6) is set or applied. This brake mechanism is shown in Fig. 6 and may be briefly described as follows: On the shaft $3'$ there is loosely or idly mounted a brake-disk 3 having an annular-flange 4 which is internally toothed and with the internal ratchet-teeth 5 of which there is arranged to engage the free toe-end of a spring-controlled pawl 6 carried by a pawl-carrier 7 mounted fast upon the shaft $3'$ and arranged to turn within the annular-flange 4 of the brake-disk 3 . The frame-members b support a horizontally-disposed bar 8 to each end of which is fastened an angle-bracket 9 . In the lower ends of these brackets 9 there is journaled a cam-shaft y mounted fast upon which is a pair of cams 12 . On each side of the brake-disk 3 there is arranged a brake-shoe or brake-jaw 13 the lower end of which is formed with an edged projection 14 and with an eye 15 . Through these eyes passes a bolt 16 the head 17 of which rests against one of the edged projections 14 and the nut 18 upon the other or threaded end of which rests against the other of the edged projections. The upper bifurcated end of each of the brake-shoes 13 is provided with a pivoted block 19 having an eye 20 through which passes the cam-shaft y ; and between the blocks 19 of the upper end of the brake-shoe 13 there is mounted upon the cam-shaft y a helical or coil-spring 21 which tends to force the upper ends of the brake-jaws 13 apart. Each of the latter is formed with a laterally-extending lug 22 which carries a cam-roller 23 . Normally the cam-shaft y is so turned that the cams 12 press against the cam-rollers 23 and thereby force the brake-shoes 13 against the brake-disk 3 , the coil-spring 21 being then compressed.

One end of the cam-shaft y is squared, as is shown at 11 , for the purpose of engaging in a hole in a suitable crank-handle (not shown). This arrangement of parts allows a workman mounted upon the load-carrying platform c to control with great accuracy the position of the latter so as to bring the same on a level with any particular tier or landing, whereby the movement of the goods to or from the platform will be greatly facilitated; for, the workman mounted upon the platform c can through the endless controlling-cable x control the driving motor e and the brake mechanism represented conventionally in Fig. 1 by the shaft y . This rock-shaft or cam-shaft y is connected with the shaft z'' by means of a sprocket-chain z' which passes over sprocket-wheels z^x, z^y , mounted on the shafts y, z'' , respectively. The last-named shaft z'' carries the switch-arm z of the reversing switch Z . When the arms y', z are in the positions shown in Fig. 1, the motor-current is interrupted and the brakes are applied or set. When the switch-arm is thrown upwardly into the dotted line position of Fig. 1, the brakes are released and the motor-current is permitted to flow so that the electric motor through the train of gearing e', e'', e^x and e^y turns the windlass-drum i in such a direction as to wind up the cable f and raise the platform c . When the switch-arm z is thrown down into the position shown by the dash-and-dot line position of Fig. 1, the brakes are released and the motor-current flows through the motor in the opposite direction so that the windlass-drum i is turned in a contrary direction by means of the train of gearing just mentioned and the cable f is unwound, whereby the platform c is allowed to descend under the influence of gravity.

From the foregoing description the operation of the machine will be readily understood and may be described as follows: If it be desired to lower the upper hinged section m (as in passing through a doorway from room to room), the operator first presses the yoke p toward the main frame so as to permit the catch or latch q to be swung inwardly over the yoke p , whereby the locking frame n is released. After the latter has been pulled outwardly into the dotted line position shown in Fig. 1, the pivoted latch q swings outwardly and its outward movement is limited by the engagement of its laterally-projecting nose or lip q'' with the adjacent plate j . In lowering the hinged upper section m , it is obvious that the first swinging movement of the top of the section will be upward and that, if provision were not made for lowering the upper sheave v , a pull would be exerted upon the cable x . In order that the pulley v may be automatically lowered (i. e., by

gravity), one of the arms of the locking frame *n* is arranged to engage the roller *t* at the lower end of the rocker-arm *s*, which lies within the locking frame *n*; and, when 5 the locking-frame is thrown outwardly into the dotted line position of Fig. 1, the pulley *v* will be swung downwardly by the force of gravity, the rocker-arm *s* following the arm *o* adjacent to it and the other or inner 10 rocker-arm *u* dropping down. Should the rock-shaft *r* not be turned sufficiently under the influence of gravity, the sheave *v* will in any event be pulled down by the tension 15 of the cable *x* as the top of the section *m* moves upwardly. In this way the switch-operating endless cable *x* is given sufficient slack to permit the hinged section *m* to be 20 swung on its hinges *k* without putting the cable under undue tension.

20 After the hinged section *m* has been swung upwardly, in restoring it to its initial or normal position, which is its operative position (see full-line position of Fig. 1), the locking frame *n* is allowed to swing 25 downwardly toward the main frame and will automatically and under the influence of gravity take its locking position, the cam face *q'* of the pivoted detent *q* permitting the yoke *p* to pass under the catch, 30 which then swings outwardly into its initial position wherein it retains the locking frame in locking position. Since, as before explained, an outward swing of the hinged upper section *m* results in an upward movement 35 of the top of the section during the initial stages of the outward swing, it is obvious that any tendency of the section to swing outwardly will be resisted by the engagement of the yoke *p* with the plates *j* of 40 the main frame.

When it is desired to raise the load-carrying platform, the switch-arm *z* is thrown upwardly into the dotted line position shown in Fig. 1; and this movement of the 45 switch-arm turns the shaft *z''* and through the sprocket-wheel *z'*, the sprocket-chain *z'*, the sprocket-wheel *y'* and the brake-shaft *y* throws the controlling-arm *y'* upwardly and therethrough moves the endless cable *x* so 50 that the upper stop *x'* is displaced downwardly a short distance. The platform *c* in its upward movement carries its arm 2 into contact with the stop *x'* and moves the 55 same upwardly into its initial position and thereby moves the endless cable so as to restore the arm *y'* to the position shown in Fig. 1; and this downward movement of the arm *y'* will be communicated through the brake-shaft *y*, the sprocket-wheel *y'*, the 60 sprocket-chain *z'*, the sprocket-wheel *z'* and the shaft *z''* to the switch-operating arm *z*, which will now be restored to its full-line 65 position shown in Fig. 1. As hereinbefore explained, when the switch-arm *z* is thrown upwardly into its dotted-line position of

Fig. 1 and the arm *y'* is correspondingly swung upwardly, the brake-shaft *y* is turned so as to release the brake.

When the arm *y'* is in the horizontal position shown in Fig. 1, the brake-shaft *y* is turned so as to set or apply the brakes and at this time the motor current is interrupted. To lower the platform *c*, the switch-arm *z* is thrown downwardly into its dash-and-dot line position shown in Fig. 1 and the arm *y'* is through the sprocket mechanism swung downwardly also, whereby the cable *x* is moved so as to displace upwardly slightly the lower stop *x''*. When the platform *c* approaches the lower limit 70 of its travel, its arm 2 strikes the lower stop *x''* and restores the same to its initial position and thereby moves the endless cable *x* to an extent sufficient to restore the arms *y', z* to their initial positions shown in full 75 lines in Fig. 1. Of course, the motor-current may be interrupted at any time by simply moving the arm *z* into its horizontal position and this may be done either by seizing the arm *z* directly or by pulling upon 80 the cable *x*. Furthermore, it is to be observed that a workman mounted upon the platform *c* may through the cable *x* control the brake-shaft *y* and the electric motor *e* so as to position with great nicety the load-carrying platform *c* at any landing or tier within the range of the machine; and this 85 feature makes possible a speedy and economical operation of the machine since the workman mounted upon the platform has at 90 hand means for directly controlling the position of the platform and is not required to shout his instructions to another workman stationed in charge of the arm *z*.

In accordance with the provisions of the 95 patent statutes we have described the principle of operation of our invention, together with the apparatus which we now consider to represent the best embodiment thereof; but we desire to have it understood that the 100 apparatus shown is only representative and that the invention can be carried out by other means.

We claim:

1. A tiering machine having a main 115 frame; an extension section hinged thereto; a load-carrying platform; mechanism for raising the latter; and a locking device carried by the extension section and arranged to serve as a means for manipulating the 120 extension section and to engage the main frame and thereby to lock the same and the extension section together.

2. A tiering machine having an extension section hinged thereto; a load-carrying 125 platform; mechanism for raising the latter; and a locking frame carried by the extension section and having a yoke arranged to engage the main frame and to lock the same and the extension section together; said 130

locking-frame being adapted to serve as a means for manipulating the extension section.

3. A tiering machine having a main frame; an extension section hinged thereto; a load-carrying platform; power-driven mechanism for raising the latter; means for controlling said power-driven mechanism; and a locking device which controls the position of said means and is carried by the extension section and arranged to engage the main frame and thereby to lock the same and the extension section together.

10 15 4. A tiering machine having a main frame; an extension section hinged thereto; a load-carrying platform; power-driven mechanism for raising the latter; a cable for controlling said mechanism; a pulley which is carried by said section and over which said cable is rove; means by which said pulley is moved to control the tension on said cable; and a locking device which controls said means and which is carried by 20 25 said section and arranged to engage the main frame and thereby to lock the same and said section together.

5. A tiering machine having a main frame; a load-carrying platform mounted free to move therein; power-driven mechanism for raising said platform; brake mechanism for controlling said power-driven mechanism; a rock-shaft by the oscillation of which said brake mechanism is applied 30 35 and released; power-controlling mechanism by which the power supplied to said power-driven mechanism is varied; connecting means by which said power-controlling mechanism is operatively connected with 40 said rock-shaft; a rocker-arm mounted on

said rock-shaft; and a cable to which said rocker-arm is operatively connected and which is controlled by said load-carrying platform, said rocker-arm being capable of being swung by said cable to apply and release said brake mechanism and vary the power supplied to said power-driven mechanism.

45 6. A tiering machine having a main frame; a load-carrying platform mounted free to move therein; an electric motor; hoisting mechanism driven by said electric motor for raising said platform; brake mechanism for controlling said hoisting mechanism; a rock-shaft by the oscillation of which said brake mechanism is applied and released; switch mechanism for controlling the electric current supplied to said electric motor; connecting means by which said switch mechanism is operatively connected with said rock-shaft; a rocker-arm mounted on said rock-shaft; and a cable to which said rocker-arm is operatively connected and which is controlled by said load-carrying platform, 50 55 60 65 70 said rocker-arm being capable of being swung by said cable to apply and release said brake mechanism and to control said switch mechanism and vary the current supplied to said electric motor.

Signed at Jersey City, in the county of Hudson and State of New Jersey, this 17th day of April, A. D., 1913, in the presence of the two undersigned witnesses.
